UNITED STATES PATENT OFFICE.

ALBERT BRANNON, OF DAYTON, OHIO, ASSIGNOR TO HOWARD F. MARSTON, OF DAYTON, OHIO.

PAPER-MAKING.

1,237,864.

Specification of Letters Patent. Patented Aug. 21, 1917.

Application filed October 22, 1912, Serial No. 727,190. Renewed February 10, 1917. Serial No. 147,929.

To all whom it may concern:

Be it known that I, ALBERT BRANNON, a citizen of the United States, and a resident of Dayton, in the county of Montgomery and State of Ohio, have invented a certain new and useful Improvement in Paper-Making, of which the following is a specification.

This invention relates to paper making and has for its object to provide an improved process of treating paper in the course of its manufacture whereby there is imparted to the product the essential features of loft-dried paper.

15 To these ends my improvement comprises manipulation and treatment set forth herein. My improved process may be carried out or effected by a variety of means, but I may employ apparatus illustrated in its 20 preferred form in the drawing accompanying this specification wherein the figure represents a diagrammatic side elevation of so much of a paper machine as will serve to illustrate the application of my improvement.

25 The object of loft-drying or pole-drying paper is to set or fix the sizing and to impart to the paper strength, toughness and stiffness, as well known in the art. It is further well known that this process is slow 30 and expensive and usually requires a further handling and finishing of the paper to put it in marketable condition. My improved process is directed to the accomplishment of this result before the paper has left the paper machine whereby when said paper is delivered from the machine it is in completed and essentially loft-dried condition.

40 I have discovered that an expeditious and satisfactory way to attain these desired results in a web of paper is to chill the web directly after it has been tub-sized and before its final drying.

45 In carrying out the steps of this process, as illustrated in the drawing above referred to I lead the damp web 3, formed by some convenient means not shown, between and around preliminary heated drying rolls 4, 5, 6 in the well known manner and thence around roll 7 in size-tub 8, in some cases squeezing off the surplus size between rolls 9, 10.

55 In making loft-dried paper it has been customary to remove the web from the ma-

chine at this point and hang the paper in lofts to season and dry. During this loft-drying process the paper absorbs the size and said size is dried in. The resultant product differs from the usual machine 60 made paper in several particulars well known to those skilled in the art, for instance, loft-dried paper has more strength, stiffness and toughness, and there is imparted thereto a character of snappiness 65 when rattled that is lacking in paper treated by other means. Loft drying also imparts to the paper a finish and appearance not obtainable heretofore by other treatment.

70 If, however, the web is passed directly from the sizing tub to the heated finishing or redrying cylinders as 19, 20, 21 it results in drawing or burning the size and to a greater or less extent in the evaporation 75 of the size thereby preventing the size from entering the pores of the paper and impregnating the fibers thereof. The paper thus produced lacks in a marked degree the desirable and valuable characteristics of 80 loft-dried paper.

Contrary to both these described methods, I, in the practice of my improvement, lead said web damp with size through a refrigerating chamber, as 25, which may be conveniently located above the machine as illustrated, if desired. The temperature of said chamber may be reduced to the requisite degree of coldness by the circulation of brine through the coils of pipe 11, 12. I preferably provide a series of cylinders as 13, 14, 15 in said chamber 25 over and around which I feed said paper web. The continuously moving web is retained in said chamber a considerable length of time for chilling it the requisite amount, thus causing the size to thoroughly permeate and to become completely absorbed by and set in said web. The web is then delivered from said chamber to the usual heated drying rolls as 100 19, 20, 21.

105 If desired, in addition to circulating the brine through pipes 11, 12, said brine may be conducted through chambers in cylinders 13 and 15 within the cooling chamber 25.

In some cases I dispense with said cooling chamber and pass the web around one or more chilling cylinders, one of which cylinders is indicated in dotted positions at 16. This cylinder may be supported in some 110

convenient manner and brine circulated through chambers therein from pipe 17.

If the web is chilled upon a cylinder as 16, exposed to the ordinary humidity of a 5 room in which a paper making machine is installed I have found it desirable to use a doctor 18 for keeping the cylinder free of moisture.

Also I may sometimes employ similar 10 doctors, not shown, on the cylinders in chamber 25 to keep those cylinders free of frost or dampness. I have found that thus chilling the damp sized web sets the size so 15 thoroughly as to prevent its removal or evaporation in the passage of the paper over the heated drying cylinders 19, 20, 21 and imparts to the paper strength, hardness 20 and toughness and other characteristics essentially the same as those produced by loft-drying.

The great saving in time, handling and loft room will be apparent to those skilled in the art.

It will be obvious to those skilled in the 25 art that various arrangements and devices for chilling the damp web between its sizing and final drying may be employed within the scope of my improvement.

It will also be obvious that it is immaterial on what type of forming machine the 30 web is made and I have therefore considered it unnecessary to illustrate means for performing such preliminary steps in the formation of the web.

I claim:

1. That improvement in the art of making paper which consists in applying size to a web or sheet of paper, then subjecting the said sized paper to cold until the size has 40 permeated and become absorbed by and set in the said paper, and then drying said paper.

2. That improvement in the art of making paper which consists in applying size to 45 a continuously moving web of paper, then subjecting the said sized web to cold until the size has permeated and become absorbed by and set in the said web, and then drying said web.

3. That improvement in the art of making paper which consists in applying size to 50 a web of paper immediately succeeding the formation and drying of said web, then

subjecting the said sized web to cold until the size has permeated and become absorbed 55 by and set in the said web, and then drying said web.

4. That improvement in the art of making paper which consists in immersing in size a web or sheet of paper, then squeezing off the surface portions of said size, then 60 subjecting the said sized paper to cold until the size has permeated and become absorbed by and set in the said paper and then drying said paper.

5. That improvement in the art of making paper which consists in immersing in size a continuously moving web of paper, then squeezing off the surface portions of said size, then subjecting the said sized web 70 to cold until the size has permeated and become absorbed by and set in the said web, and then drying said web.

6. That improvement in the art of making paper which consists in immersing in size a web of paper immediately succeeding the formation and drying of said web, then squeezing off the surface portions of said size, then subjecting the said sized web to cold until the size has permeated and become absorbed by and set in the said web, 80 and then drying said web.

7. That improvement in the art of making paper which consists in applying size to a web or sheet of paper, then subjecting 85 said treated paper to cold until the size becomes set and then drying the paper, said chilling and drying operations being adapted to impart to the paper substantially the characteristics of loft dried paper.

8. That improvement in the art of making paper which consists in applying cold to a web or sheet of paper which has been previously sized and then drying the paper, said application of cold to the sized paper 95 being adapted to impart to the paper substantially the characteristics of loft dried paper.

Signed at Dayton, in the county of Montgomery, and State of Ohio this 19th day of Oct., 1912, before two subscribing witnesses.

ALBERT BRANNON.
